UNITED STATES PATENT OFFICE.

ISIDOR KITSEE, OF PHILADELPHIA, PENNSYLVANIA, ASSIGNOR OF ONE-HALF TO WILLIAM J. LATTA, OF PHILADELPHIA, PENNSYLVANIA.

TELEGRAPHY.

No. 846,415.

Specification of Letters Patent.

Patented March 5, 1907.

Application filed February 26, 1906. Serial No. 302,984.

To all whom it may concern:

Be it known that I, ISIDOR KITSEE, a citizen of the United States, residing at Philadelphia, in the county of Philadelphia and State of Pennsylvania, have invented certain new and useful Improvements in Telegraphy, of which the following is a specification.

My invention relates to an improvement in telegraphy, and has more special reference to the transmitting device.

On land-lines the usual arrangement of telegraphing is that a transmitting-key opens and closes a line provided with a source of current, having one pole always connected to this line. The transmitting-key is usually a metallic base, a lever electrically in connection with said base, and the front contact electrically insulated from said base. One part of the line is connected to the base, and therefore the lever and the other part of the line is connected to the contact. The downward stroke of the lever closes the line, and the releasing of the lever opens the line. On lines with great capacity—such, for instance, on cables aerial or subterrane—the telegraphing with one polarity is not advantageous, for the reason that the line "chokes" if not enough time is given after each impulse to discharge the same.

My object is to produce a transmitting device whereby with the aid of a common Morse key reversals may be sent over the line, thereby making it possible to transmit messages over a cable at a comparative great speed.

As this my invention has only reference to the transmitting device, it is not necessary to describe in detail the receiving device. It suffices to say that the same should consist of a polarized device.

Referring to the drawing, Figure 1 represents in diagrammatic view my transmitting device in connection with the key proper; and Fig. 2 is a perspective view of the transmitting device, the key excluded.

A is the key proper; B, the attachment to the key in its entirety. The key comprises the metallic base 8, the lever 1, the point g, the switch 5, and the contacts 2 and 6. The lever is, as usual, in electrical contact with the base, and the point is, as usual, insulated from said base. In the transmitting-keys used to-day on land-lines the key closes the line normally—that is, when not in use—

through a switch substantially as shown in the drawing; but in the usual arrangement the contact 2 is connected with the point g, and the switch is connected with the metallic base. When the operator desires to telegraph, he opens the switch—that is, moves the same to the right and then opens and closes the line through the movement of the lever of the key. In my arrangement the key is not connected to the line, but is connected to a localized circuit, and its connection, as to the line, the key, and sources of current, is as follows: The battery 4, here shown as to consist of three cells, is connected, through wire 18, with one pole to the switch 5 of the key A and with the other pole to the junction of wire 20, connecting together the coils of the two electromagnets 7 and 10. The other terminal of electromagnet 7 is connected through wire 21 with contact 6 of the key, and the other terminal of electromagnet 10 is connected, through wire 17, with point g of the key. The electromagnet 10 is provided with armature 15 and in juxtaposition thereto the contact-points 11 and 12, and the electromagnet 7 is provided with armature 16 and in juxtaposition thereto the contact-points 13 and 14. The contact-points 12 and 14 are electrically connected with each other, so also are in electrical connection the contact-points 11 and 13. A source of current 3, here shown as to consist only of two cells, but in reality to consist of such number of cells as the line requires, is connected to the pole, here shown as a positive, with contact 11 and through the same with contact 13 and is connected with the other pole to contact 12 and through the same with contact 14. The armature 15 is connected to the line L, and the armature 16 is connected to the ground G.

Normally—that is, when the device is idle—the switch 5 of the key is in a position so as to contact with 2. This contact is insulated from all other parts of the key proper. The circuit containing electromagnet 7 is therefore open, so also is the circuit containing electromagnet 10 open, and the armatures 15 and 16, being provided with springs, will rest on the points 12 and 14, respectively. A circuit is therefore established over the line L direct to the ground and consisting of armature 15, contact 12, contact 14, armature 16, and the ground G.

When the operator desires to transmit messages, he first of all moves the switch, so as to connect with contact 6, thereby closing the circuit containing the electromagnet 7.

- 5 This will result in the energizing of electromagnet 7 and the drawing of the armature 16 from contact 14 toward to and in connection with contact 13. The direct circuit between the line and ground is thereby broken and 10 the circuit is established, including line L, armature 15, contact 12, battery 3, contact 13, armature 16, and ground G. In this arrangement the positive pole of the battery is connected to the ground and the negative pole to the line. An impulse, therefore, will 15 flow over the line in the direction of the unfeathered arrow. This impulse is called by me the "clearing-impulse" and will only affect the translating device at the receiving-station in a manner so as to produce what is 20 called a "space." After the closing of the circuit containing electromagnet 7 he manipulates the key in the usual manner—that is, he depresses the lever for a short period to 25 transmit a dot and for a long period to transmit a dash, and he allows the key to remain open for a short period to denote a short space and for a long period to denote a longer space. The coil of electromagnet 7 is, 30 considered in relation to the coil of electromagnet 10, of comparative high resistance, and I had good results with a device in which the coil of electromagnet 7 had twenty-five ohms and the coil of electromagnet 10 had five 35 ohms. The proportion, therefore, of one to five seemed to be satisfactory for all purposes.

As long as the lever of the key is not depressed the current will flow through electromagnet 7, and the strength of three cells, or of as many cells as are desired, is sufficient to energize the same and move the armature from its resting-place; but as soon as the lever of the key is depressed the circuit embracing electromagnet 10 is closed, and as this circuit is of lower resistance than the circuit containing electromagnet 7 it is obvious that the greatest amount of current will flow through the coil of electromagnet 10. The 45 electromagnet 7 will then be to the greatest extent demagnetized, and the armature 16 will again be drawn by its spring toward to and in connection with contact 14; but the armature 15 of electromagnet 10 will be drawn from its resting-place 42 toward to 50 and in contact with point 41. This operation will result in changing the connection of the battery 3 as to the line and ground and of establishing a circuit embracing the line L, armature 15, point 41, positive pole of battery 3, points 12 and 14, armature 16, and ground G. The battery, therefore, is connected with this positive pole to the line and negative pole to the ground—that is, opposite from its former connection. As long as

the operator holds the lever depressed, the armatures 15 and 16 will remain in this position, and as the receiving instrument, a polarized device, requires an opposite current to move its armature to an opposite direction this armature will remain in a position as brought about by the flow of this current, and a focal circuit attached thereto will be closed as long as this armature remains there; but as soon as the operator releases the lever the circuit, including the coil of electromagnet 10, is broken, and its armature will fall downward to stop 12, and the current flowing through circuit 18 and 21 will energize the coil of electromagnet 7, bringing 80 its armature to stop 13 and reversing the flow of the current.

Persons versed in the art will readily understand that with this arrangement reversals are sent over the line, and if a proper receiving instrument is included in the line at the receiving-station the same may be made to translate these reversals into dots and dashes and be read by the operator in the usual manner.

In Fig. 2 the binding-posts, negative and positive, designate the places where the battery 3 is to be attached, the binding-posts G and L the places where the ground and line have to be connected. The binding-post 25 designates the place where one terminal of electromagnet 10 is to be connected, the binding-post 27 where one terminal of electromagnet 7 is to be connected, and the binding-post n designates the place where the junction of the wire 20 is connected. In all other respects the designation of similar parts is similar to the designation in Fig. 1.

I have described the device as being connected to line and ground, respectively; but it is obvious that as a metallic return is equal to a ground return the expression "ground" includes a metallic as well as earth return.

Having now described my invention, what I claim as new, and desire to secure by Letters Patent, is—

1. In telegraphy, a transmitting device comprising the key proper, two localized circuits, each containing an electromagnet, the resistance of both these circuits differing from each other, an armature for each electromagnet, means to connect said armatures to the line and ground respectively, a source of current for the line and means to change the connection of said source as to the line and ground through the movement of the lever of the key proper.

2. In a telegraphic transmitting device, a key, two localized circuits, one of said localized circuits adapted to be opened and closed through the key-switch and the second of said localized circuits adapted to be opened and closed through the key-lever.

3. A telegraphic transmitter embracing the key proper, two localized circuits, each

circuit containing an electromagnetic device, the resistance of one of said devices greater than the resistance of the second and means to close each of said circuits independently of each other; means integral with said electromagnets to connect the line and ground directly, a source of current for said line and means to connect said source with one or the other of its poles to the line and ground respectively, said means dependent on the operation of said key.

4. In a device of the class described, transmitting means, two circuits operatively related to said means, each circuit comprising an electromagnet, means at said transmitting means to make operative one or the other of said circuits, a source of current, and means operatively related to said electro-

magnets to connect said source with the positive or negative pole to a line of transmission. 20

5. A telegraphic transmitter comprising the manually-operated key proper and two electromagnets in operative relation to said key, an electric circuit for each of said electromagnets, means integral with said key to 25 make operative one or the other of said circuits and means integral with each of said electromagnets to connect a source of current to the line of transmission with the positive or negative pole. 30

In testimony whereof I affix my signature in presence of two witnesses.
